US00D771987S

(12) **United States Design Patent** (10) Patent No.: **US D771,987 S**
(45) Date of Patent: **** Nov. 22, 2016**

(54) **BOUNCER SEAT**

(71) Applicant: **Thorley Industries LLC**, Pittsburgh, PA (US)

(72) Inventors: **Robert D. Daley**, Pittsburgh, PA (US); **Elijah M. Wiegmann**, Natrona Heights, PA (US); **Justin Adleff**, Pittsburgh, PA (US); **Parker Trow**, Pittsburgh, PA (US); **Daniel Kanitz**, Pittsburgh, PA (US)

(73) Assignee: **Thorley Industries LLC**, Pittsburgh, PA (US)

(**) Term: **15 Years**

(21) Appl. No.: **29/533,624**

(22) Filed: **Jul. 20, 2015**

Related U.S. Application Data

(63) Continuation of application No. 29/500,889, filed on Aug. 29, 2014, now Pat. No. Des. 737,061.

(57) **CLAIM**

The ornamental design for a bouncer seat, as shown and described.

DESCRIPTION

FIG. 1 is a front perspective view of a bouncer seat in accordance with the invention;

FIG. 2 is a front side view thereof;

FIG. 3 is a rear side view thereof;

FIG. 4 is a right side view thereof;

FIG. 5 is a left side view thereof;

FIG. 6 is a top plan view thereof; and,

FIG. 7 is a bottom plan view thereof.

The broken lines illustrating portions of the bouncer seat form no part of the claimed design.

1 Claim, 7 Drawing Sheets
